UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

CONCRETE-PAVER BUCKET MECHANISM.

Application filed March 1, 1923. Serial No. 622,026.

To all whom it may concern:

Be it known that I, ERICH H. LICHTENBERG, a citizen of the United States, residing at Milwaukee, in the county of Milwaukee, 5 and State of Wisconsin, have invented certain new and useful Improvements in Concrete-Paver Bucket Mechanisms, of which the following is a specification.

In my Letters Patent No. 1,141,470 issued 10 June 1, 1915 and No. 1,411,217 issued March 28, 1922 are described certain types of paving machines involving boom and bucket distributing mechanism for concrete. It is the object of this invention to provide an improved 15 construction of bucket mechanism of the types disclosed in said Letters Patent, the features of improvement residing primarily in the means for supporting the bucket upon the boom, the trolley or carriage assemblage of parts, and the operating means intermediate the trip mechanism on the carriage or trolley and the door or doors of the bucket.

It is desirable that the bucket with its contents be supported from the boom in stable equilibrium, of course, to which end I have designed the trolley from which the bucket is hung in a peculiar and advantageous manner. Among other things I utilize supporting rollers or wheels on the carriage, peculiarly mounted as regards their connection with said carriage or trolley, so as to have a special movement relative to the carriage or trolley in the nature of an equalizing action 30 or adjustment. This self equalizing feature, so to speak, as regards the trolley wheels or rollers has a tendency to stabilize the bucket in its travel, and in respect to its center of gravity when loaded, all in a manner which 35 would appear more fully after an understanding is had of the detail construction of my improvements.

The feature of the invention which involves the mounting of certain trip mechanism for dumping the bucket, upon a center body member, to which the trolley wheel brackets and the bucket hangers may be bolted, is also especially desirable in that it facilitates the putting together or assembling 45 of the various parts of the trolley or carriage, and the application of the same to the boom, as well as the removal from the boom when such removal becomes necessary.

The special opening and closing connections for the door or doors of the bucket,

intermediate the door or doors and the trip mechanism on the trolley, are such as to give a very positive action to the door in opening and in its restoration to closed condition, and furthermore the connections are so arranged in relation to the door as to obtain a maximum amount of leverage in maintaining the door closed and in drawing it to closed position, as the case may be. I furthermore use a special formation of rollers for the trolley engaging the boom so that the pressure load of the bucket and its contents is applied to the boom channels or tracks as closely as possible to the heels of said channels.

70 In the accompanying drawings,

Figure 1 is a side elevation of a boom and bucket mechanism, embodying the invention, dotted lines showing the bucket door swung to an open position.

75 Figure 2 is a front elevation of the same, or a view which looks toward the bucket from its left hand side as viewed in Fig. 1.

Figure 3 is a top plan view of the body of the trolley.

80 Figure 4 is a side elevation of said body, and

Figure 5 is a detail rear view of the trolley body.

85 In the drawings, A denotes a boom comprised of a pair of channels suitably fabricated together to provide a unitary boom body or support. The bucket is designated B, and the body of the trolley is designated 1 (see Fig. 2). The bucket B, generally speaking, is of the type illustrated in my Letters Patent No. 1,411,417, previously referred to, in that it is of a spreading type as known in the art, being equipped at its bottom with a door 2 adapted to swing 90 downwardly a predetermined distance to render operative to a greater or less extent the bottom opening of the bucket and deliver the contents of the bucket to the sub-grade in a layer of a predetermined thickness. The means for operating the door are comparatively simple, including links 3 at opposite sides of the bucket B, which links are pivotally connected at their lower ends to the door 2 near the free edge of the latter. At their upper ends the links are pivotally connected at 4 with arms 5, carried by a rock shaft 6. The rock shaft 6 is mounted in suitable bearing brackets 7, secured to the upper portion of the bucket B, 105 110

and at its center portion the rock shaft has a rocker arm 8. The center arm 8 is attached in a suitable manner as by a connection generally designated C to a trip link 9, the upper end of which is pivotally connected to a pair of trip arms 10 pivotally mounted on the trolley by a trip shaft 11. This shaft 11 may be equipped with a closing arm 12, (seen best in Fig. 2) adapted 5 to be tripped closed by means of a cam or some obstruction device in its path of movement, as the bucket B is brought back to a position on the boom A wherein it is ready to receive a fresh batch of concrete or material to be distributed thereby. The tripping mechanism utilized according to the present invention is generally well known in the art being of the shuttle type disclosed by my Patent No. 1,141,470 aforesaid, and 10 will be referred to a little more fully after description of the trolley or carriage construction. The trolley or carriage comprises the body 1, previously mentioned, shown best in Figures 3 to 5 inclusive. 15 This body 1 has the laterally extending arms 13 to which are bolted the hangers 14 which connect the bucket B rigidly with the trolley or carriage 1. Likewise there are bolted to opposite sides of said body 1, and 20 to its lateral arms 13 the side brackets 15, which form the sides of the trolley proper. The sides or brackets 15 are equipped with rearwardly extending curved horns or arms 16, each of which has a roller or trolley 25 wheel 17 engaging in the channel of an adjacent channel member of the boom A. Intermediate their ends, the sides 16 of the trolley are equipped with the pivoted equalizing arms 18 at the opposite ends of each 30 of which are provided rollers 19 that correspond in general formation with the rollers 17 previously mentioned. The equalizing arms 18 are really carried by vertical extensions of the sides or side brackets 15 of the trolley. The purpose of these equalizing parts 18 is to provide for an automatic adjustment of the rollers 19 to equilibrate the pressure load transmitted to the boom therethrough. Obviously when the 35 bucket B is filled there is a slight variation in its center of gravity due to the slight variation in the piling up of the concrete or material fed into the bucket B to be distributed. Notwithstanding such slight variation the pressure load is distributed 40 equally on the portions of the boom A engaged by the rollers 17 and 19, incident to the action of the arms 18 aforesaid.

The rollers 17 and 19 are carried by the 45 trolley at a slight upward angle and are formed with rounded faces so as to fit as far as possible into the channels of the channel members of the boom A and, therefore, bring the pressure load as close as possible 50 to the heels of the channels, which channels

act as tracks for the trolley in the movement of the latter.

Without describing immaterial details the trip mechanism for tripping the link 9 over dead center in the well known manner of operation of mechanisms such as shown, I might note that the bucket B and its supporting trolley 1—15—14 are moved along the boom A by means of a cable 20, seen in section in Figure 2, and clamped to a shuttle 21 supported in guides 22 of the body 1 of the trolley. On this shuttle is carried the trip member 23 adapted under controlled adjustment to engage the upper end of the link 9 and shift the same over the dead center line of the shaft 11 to cause the link and its supported parts to drop as shown by dotted lines in Figure 1. The shuttle 21 with its cable clamping means, trip member 23, and other detail parts such as the shaft 11, link 9 and arms 10, are adapted to be assembled in and on the body 1 of the trolley and handled with said body as a unit. The parts 15 and 14 are then adapted to be bolted to the body. The foregoing makes an excellent structure for practical manufacturing purposes.

It is notable furthermore that the connection generally designated C may comprise a housing for a spring which establishes a yielding connection intermediate the link 9 and the arm 8, substantially as disclosed in my Patent 1,411,217 desirable where a door such as the door 2 may not close with precise tightness owing to an obstruction between it and the bucket.

The links 3 are guided somewhat by brackets 24 off-standing from the sides of the bucket B and these brackets additionally form stops capable of coacting with stop members 25 on the links 3, which stop members 25 determine the extent of opening of the door 2, by engagement with the brackets 24. A series of openings 26 in the links 3 and suitable pins to pass through said openings and the stops 25 enable the adjustment of the stops 25 for the purpose of varying the degree of opening movement of said door 2, and thereby regulate the thickness of the stream or layer of concrete or plastic material fed from the bucket in its distributing action. A single door 2, is illustrated in the drawings but obviously companion doors might be utilized within the purview of the invention with equal advantage as regards the efficiency of the bucket distribution method.

Figure 1 shows that the boom A is supported upon a horizontal axis 27 comprising a bracket which in turn is pivoted on a vertical axis 28, the latter carried by an off-standing arm 29 ordinarily mounted so as to project from the frame of a concrete paving machine which comprises a mixer. The formation of the trolley or carriage which

supports the bucket as described herein is advantageous, owing to the provision of the extensions, horns or arms 16. In the present construction the carriage or trolley may 5 be said to be canted so that its innermost portion may over-hang the point of pivotal support of the boom and enable the bucket to be brought well under said pivotal support in toward the mixer discharge chute to 10 receive the plastic or other material from the latter.

The shuttle, cable clamp, and its mounting on the trolley; also the trip member carried by the shuttle are features of construction shown largely in the copending application of George W. Frost filed January 27, 1923, Serial No. 615,192.

Having thus described my invention what I claim as new and desire to secure by Letters Patent is,

1. In combination, a boom, a distributing bucket to traverse the same and supporting means for the bucket to enable it to travel on the boom including a trolley, said trolley 25 comprising sides, equalizing arms pivoted to said sides in the longitudinal plane of the beam, and rollers on said arms engaging the boom to travel thereon.

2. In combination, a boom, a distributing bucket to traverse the same and supporting means for the bucket to enable it to travel on the boom including a trolley, said trolley comprising sides, equalizing arms pivoted to 35 said sides, and rollers on said arms engaging the boom to travel thereon, hangers connecting the trolley with the bucket near one end of the latter, and said trolley comprising extensions projecting toward the end of the bucket remote from that connected 40 with the hangers, and rollers on said extensions engaging the boom.

3. In combination, a boom, a trolley thereon comprising sides having rearward extensions, rollers mounted on said extensions and 45 engaging the boom, equalizing arms pivoted to the sides of the trolley intermediate the ends of the latter, rollers on the ends of said arms and engaging the boom, a bucket and hangers connecting the bucket and said 50 trolley.

4. Means as claimed in claim 3, wherein the hangers extend from the trolley from points substantially in the plane of said equalizing arms.

5. In combination, a boom, distributing bucket mechanism thereon comprising a bucket, a trolley supporting the bucket on the boom, said trolley comprising a body having a longitudinal guideway at its upper portion, bucket door tripping mechanism assembled in the body beneath said guideway to provide a trolley body and tripping mechanism unit, and roller devices 60 secured to the body above said guideway and intermediate the boom and the trolley. 65

6. In combination, a boom, distributing bucket mechanism thereon comprising a bucket, a trolley supporting the bucket on the boom, said trolley comprising a body, bucket door tripping mechanism assembled 70 in the body to provide a trolley body and tripping mechanism unit, side members detachably applied to the body of the trolley and provided with longitudinally extended roller carrying arms, and roller devices intermediate the body of said side members and the boom.

7. In combination, a boom, distributing bucket mechanism thereon comprising a bucket, a trolley supporting the bucket on 80 the boom, said trolley comprising a body, bucket door tripping mechanism assembled in the body to provide a trolley body and tripping mechanism unit, side members applied detachably to opposite sides of the 85 trolley body, equalizing arms pivoted on said side members and a pair of rollers carried by each equalizing arm and engaging the boom.

8. In combination, a boom, distributing 90 bucket mechanism thereon comprising a bucket, a trolley supporting the bucket on the boom, said trolley comprising a body, a bucket door tripping mechanism assembled in the body to provide a trolley body and 95 tripping mechanism unit, detachable side members applied to the trolley body and formed with rearward extensions, rollers carried by said extensions and engaging the boom, equalizing arms pivoted between their 100 ends to said side members, and rollers on the ends of said equalizing arms and engaging the boom.

9. In combination, a boom, distributing bucket mechanism thereon comprising a 105 bucket, a trolley supporting the bucket on the boom, said trolley comprising a body, bucket door tripping mechanism assembled in the body to provide a trolley body and tripping mechanism unit, side members attached to said body and having a longitudinally extended arm, rollers supporting the 110 arm and side members on the boom, and hangers connected with the trolley body and the bucket to support the latter on the 115 trolley.

10. A distributing bucket device substantially as described comprising a bucket, a door for said bucket, link members connected to the door and arranged at opposite 120 sides of the bucket, a shaft mounted on the upper portion of the bucket, arms connecting the link members and the shaft, a trolley to support the bucket, and tripping mechanism on the trolley connected with said 125 shaft for rocking the latter to open the door.

11. A distributing bucket device substantially as described comprising a bucket, a door for said bucket, link members connect- 130

4
ed to the door and arranged at opposite sides of the bucket, a shaft mounted on the upper portion of the bucket, arms connecting the link members and the shaft, a trolley 5 to support the bucket, tripping mechanism on the trolley connected with said shaft for rocking the latter to open the door, and stop means cooperating with the link members to limit the extent of movement there- 10 of and thereby regulate the degree of opening movement of the door.

12. A distributing bucket device substantially as described, comprising a bucket, a door for said bucket, link members connect- 15 ed to the door and arranged at opposite sides of the bucket, a shaft mounted on the upper portion of the bucket, arms connecting the link members and the shaft, a trolley to support the bucket, tripping mechanism 20 on the trolley connected with said shaft for rocking the latter to open the door, stop

means cooperating with the link members to limit the extent of movement thereof and thereby regulate the degree of opening movement of the door, together with pins and openings intermediate the link members and the stop members for the adjustment of the latter as described. 25

13. In combination, a boom comprising opposite channels forming tracks, distributing bucket mechanism including a bucket, a trolley supporting said bucket, and rollers intermediate the trolley and the boom and formed with convex treads formed to engage the heel portions of the boom to bring the pressure load of the bucket and its contents to the opposite heels of the boom channels in the traverse of the rollers along the latter. 30

In testimony whereof I affix my signature. 35

ERICH H. LICHTENBERG.
